AUTOMOBILE

Leslie A. Dawes, Torrance, Calif.

Application May 27, 1957, Serial No. 46,350

Term of patent 7 years

(Cl. D14—3)

Fig. 1

Fig. 2

Fig. 3

I claim:

The ornamental design for an automobile, substantially as shown.
